ICE FISHING TIP-UP SIGNAL

Victor F. G. Plsner, 219 Main St., Horicon, Wis.

Filed Feb. 27, 1963, Ser. No. 73,733

Term of patent 14 years

(Cl. D72—1)

FIG. 1 is a perspective view of the top of an ice fishing tip-up signal embodying applicant's design, showing the flag in its cocked position.

FIG. 2 is a top plan view of an ice fishing tip-up signal of applicant's design, showing the flag in its cocked position.

FIG. 3 is a front elevational view of an ice fishing tip-up signal of applicant's design, showing the flag in its cocked position.

FIG. 4 is a side elevational view of an ice fishing tip-up signal of applicant's design, showing the flag in its released position.

FIG. 5 is a perspective view of the bottom of an ice fishing tip-up signal of applicant's design.

I claim:

The ornamental design for an ice fishing tip-up signal, as shown.
